UNITED STATES PATENT OFFICE

MIRIAM DARB, OF WILKINSBURG, PENNSYLVANIA

STOCKING SUPPORTER

Application filed June 13, 1928. Serial No. 284,928.

My invention relates to means for supporting stockings.

One object of my invention is to provide means for supporting stockings of silk or sheer material without subjecting the threads to excessive tension stresses that would cause them to break and become "runners".

Another object of my invention is to provide means for supporting stockings without subjecting the wearer to the discomfort of tight garters which tend to limit the freedom of blood circulation.

Another object of my invention is to provide means for supporting stockings which shall utilize the advantages of supporters and garters without being affected by their disadvantages.

Stockings are supported by devices of two general classes, garters and supporters with

claps. Supporters serve effectively to hold the stocking in place, but due to the manner in which the supporter clasps are secured to a stocking, any unusual movement of the body of the wear may impose an excessive stress upon the threads of the stockings and cause them to break and become "runners". The threads of stockings of silk or of other sheer material break quite easily under such conditions and ruin the stocking.

Garters, on the other hand, have no tendency to produce "runners". The disadvantage of garters, however, is that they must be worn tightly to be effective. Under such conditions they cause discomfort to the wearer, since they affect the blood circulation. Worn loosely, they are of little benefit.

The object of my invention is to provide a method of supporting stockings that will utilize the advantages of both garters and supporters, and obviate the disadvantages.

The manner in which I obtain the desired result is to provide the ordinary garter with one or more rings or clips to each of which a supporter clasp may be attached. The rings or clips are secured to the outer surface of the garter in such manner as to permit the supporter clasp to be readily attached and detached. The garter then functions as a friction ring around the stocking and may

be worn relatively loosely. The actual supporting effort is provided by the supporters on the auxiliary rings.

Since no forces are imposed directly upon the threads of the stockings, there is no tendency to break the thread. 55

The manner in which the parts are arranged will be understood upon reference to the accompanying drawings, in which Fig. 1 is a view showing the garters supported by a supporter band; and Fig. 2 is an enlarged perspective view of the garter I employ in my invention. 60

As is illustrated, a stocking is to be supported and held in place by a garter 2 and supporting means 3, which may be a corset, corselette or supporter strap. The supporting means 3 is provided with the usual supporters 4 which have a clasp 5 secured to the end thereof. 65

The garter 2 consists of the usual encircling band 6 and end clips 7 and 8 for closing the band about the stocking. Adjusting means are also usually provided.

In addition to the above usual parts of a garter, I provide, preferably, two rings or eye clips 11 and 12, secured to the outer surface of the garter by two anchoring elements 13 with sufficient looseness relative to the garter to permit the parts of the clasp 5 to be readily inserted or withdrawn while the garter is closed around the stocking. 75

The supporter clasps may therefore be easily attached to, or detached from, the rings 11 and 12, without affecting the garter. 85

I have found that garters supported as described herein, may be worn with relative looseness and comfort, and yet serve to hold the stockings properly in place. Since no direct tension stresses are imposed upon the stocking threads, there is no tendency to break the threads, and the stockings may be used for a longer period of time. 90

The rings 11 and 12 may take any suitable form which will permit ready attachment and detachment of a supporting clasp. 95

My invention is therefore not limited to elements of the exact design illustrated, but may be variously modified without departing 100

from its spirit and scope, as set forth in the appended claims.

I claim as my invention:

1. Means for supporting a silk stocking, comprising a substantially continuous garter band constituting a single loop and a supporting ring secured to the outer surface of the band, said supporting ring being loose to permit a supporting clip to be attached and detached, but held against the outer surface of the loop.
2. Means for supporting a silk stocking, comprising a substantially continuous garter band of constant width constituting a single loop of substantially constant width, a ring on each side of the band whereby the band may be supported at two points and two elements disposed entirely on, and secured to, the outer surface of the band for holding each ring in place with sufficient looseness to permit a clasp to be readily attached to or detached from the rings without disturbing the binding action of the garter band, the rings serving to pull the supporting elements together, when functioning, and thereby to slightly tighten the band around the stocking.
3. Means for supporting a silk stocking, comprising a substantially continuous garter band constituting a single loop, a pair of spaced elements secured on, and along, the outer surface of the band on opposite sides thereof, and a ring held in position, by, and between each pair of spaced elements, against the outer surface of the band.

In testimony whereof, I have hereunto subscribed my name this 6th day of June, 1928.

MIRIAM DARB.
